CLAIM

The ornamental design for a pet carrier, as shown and described.

DESCRIPTION

FIG. 1 is a front, right and top perspective view of a pet carrier, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the pet carrier that form no part of the claimed design.

The double broken lines depicts the part of the pet carrier zipper that does not form part of the required design.

1 Claim, 8 Drawing Sheets(56)
